ATTORNEY'S

UNITED STATES PATENT OFFICE

104,967

DESIGN FOR A STOVE

Christopher L. Hardwick, Cleveland, Tenn.

Application May 1, 1937, Serial No. 69,120

Term of patent 3½ years

To all whom it may concern:

Be it known, that I, Christopher L. Hardwick, a citizen of the United States, residing at Cleveland, county of Bradley, and State of Tennessee, have invented a new, original, and ornamental Design for a Stove, of which the following is a specification, reference being had to the accompanying drawing, forming part thereof.

Figure 1 is a perspective view of a stove showing my design and

Figure 2 is an end view of the stove.

That side of the stove which cannot be seen in the drawing presents a substantially plain appearance.

I claim:

The ornamental design for a stove, as shown and described.

CHRISTOPHER L. HARDWICK.
